UNITED STATES PATENT OFFICE.

OTTO J. F. FAJEN, OF STOVER, MISSOURI.

VALVE FOR INTERNAL-COMBUSTION ENGINES.

Application filed March 31, 1924. Serial No. 703,208.

To all whom it may concern:

Be it known that I, OTTO J. F. FAJEN, a citizen of the United States, and a resident of Stover, county of Morgan, and State of Missouri, have invented a new and useful Improvement in Valves for Internal-Combustion Engines, of which the following is a full, clear, and exact description.

My invention relates to improvements in valves for internal combustion engines, and it consists in the combinations, constructions, and arrangements herein described and claimed.

An object of my invention is to provide a valve construction in which the intake and exhaust valves are housed in one valve casing, thereby obviating the necessity of a valve casing for each valve, and thus reducing the cost.

A further object of my invention is to provide a device of the type described, in which two valves may be located in substantially the same space as one.

A further object of my invention is to provide a device in which the incoming charge is heated so as to provide a more efficient explosive mixture while the exhaust gas is cooled, through the giving up of its heat to the incoming charge.

A further object of the invention is to provide a device in which one push rod and one cam will serve for operating both the inlet and the exhaust valves.

Other objects and advantages will appear in the following specification, and the novel features of the invention will be particularly pointed out in the appended claims.

My invention is illustrated in the accompanying drawings, forming part of this application, in which—

Figure 1 is a vertical sectional view through the valve casing and the cam shaft, showing the valves in a position for admitting the mixture into the cylinder.

Figure 2 is a similar sectional view through the valve casing, showing the position of the valves during the working and compression strokes, and

Figure 3 is a similar view showing the position of the valves during the exhaust stroke.

My invention is primarily designed for a four cycle engine. It may be applied to cylinders of any suitable size. In the drawings, I have shown a portion of a cylinder 1, having a water jacket 2 of the usual type.

At 3 I have shown the exhaust passages which may lead to an exhaust manifold (not shown). Mounted integrally with the exhaust pipes 3 is a cylindrical guide member 4.

At 5 I have shown an intake manifold which is stationary, being preferably bolted to the cylinder head. Integral with this intake pipe is an outer cylinder 6, having a closed end 7, the ends being integral with an inner fixed cylinder 8, which is braced at the bottom by a spider 9. An upper valve casing portion 18 is provided, having a central opening through which the valve stem 19 extends.

The valve stem 19 has secured at its lower end a valve 10 which is arranged to engage a valve seat 11 formed on the head of the cylinder. Normally, the valve 10 is kept in a closed position, such as that shown in Figure 2, and to this end a pin 12 is provided which passes through the valve stem, and a spiral spring 13 bears at one end on the spring and at the lower end on the partition 80 or end 7.

The valve stem 19 passes through a sleeve 14, having a top portion 15. A lighter spring 16 bears on this head 15, and against a pin or collar 17 which is secured to the valve stem. The lower end of the sleeve 14 is connected with a cup-shaped valve member 20, having a central opening, the edge of which constitutes a valve seat 21 for the upper edge of the valve 10. The outer lower edge 22 of the valve member 20 constitutes a valve which is arranged to engage against a valve seat 23 formed in the cylinder head.

In Figure 1, I have shown the crank shaft 24 and the driving gears 25 and 26 diagrammatically. The cam shaft 27 has provided thereon a cam having a raised portion 28 and a lower portion 29. These are adapted to engage the roller 30 on the push rod 31, which, through the medium of the usual tappet 32, operates the valve stem 19.

From the foregoing description of the various parts of the device, the operation thereof may be readily understood. Figure 1 shows the valves in the intake position. The mixture is coming through the pipe 5 and passing downwardly into the cylinder, as indicated by the arrows. When the wheel 30 leaves the portion 28, and engages the cylindrical surface 29 of the cam, the valve will close, owing to the action of the

springs 13 and 16. Figure 2 shows the valves in their closed position. The charge is compressed and ignited in the usual manner, and during the compression and working strokes the valves remain closed. The cam shaft is revolved in the direction shown by the arrow in Figure 1, so that when the lower portion 29 engages the roller, it will push the valve stem downwardly. As the pins or collars 12 and 17 move downwardly with the valve stem, the valves 10 and 20 will move downwardly to the position shown in Figure 3. The spring 13, being a stronger spring and not having a bodily movement, will hold the valve 10 against the valve 20. The exhaust gases will pass out, as indicated by the arrows in Figure 3, into the exhaust pipe 3, and thence into the exhaust manifold (not shown). When the portion 28 of the cam is reached, it will tend to force the valve stem 19 down still farther. The valve member 20 will move downwardly until it engages the valve seat 23 (see Figure 1), while the valve 10 will continue to move downwardly and will leave its seat at 21, thus permitting the admission of the charge in the manner already described. This cycle of operation is repeated as long as the engine is working.

It will be observed that the inrush of gas is over the hot valve 10. This tends to impart heat to the mixture and thus to increase its efficiency. On the other hand, the exhaust passes by the cooler valve 20, and the exhaust gases are thereby cooled. The heating of the valve 20, of course, contributes to the heating of the incoming mixture, so that the device has a double purpose of heating the incoming gases and cooling the exhaust gases.

The provision of the valve casing having the two valves renders the construction compact, besides obviating the necessity of an extra cam, push rod and tappet.

I claim:

1. A valve construction for internal combustion engines comprising a valve stem, a

valve secured to said stem, an auxiliary valve movable relative to said first named valve individual springs for controlling 50 said valve, the longitudinal movement of the valve stem in one direction serving to move both valves against the tension of their respective springs to a position to permit exhaust of gases within the cylinder, 55 and a further movement of the valve stem bringing the auxiliary valve in a position to close the exhaust and to open the intake valve.

2. The combination with an internal combustion engine, of a valve construction comprising a valve stem, a valve secured to said stem, an auxiliary valve movable relative to said first named valve, spring means for holding 60 said valves normally in engagement, whereby the intake is closed, and means for moving both valves simultaneously to bring the auxiliary valve in position to close the exhaust, the further movement of the first named valve causing the 65 separation of the two valves and the opening of the intake.

3. The combination with the cylinder of an internal combustion engine having upper and lower valve seats in the head thereof, of 75 a valve arranged to engage said lower seat, an auxiliary valve arranged to engage said upper seat, each of said valves having a face arranged to engage the face of the 80 other valve for controlling the passage of gases.

4. The combination with the cylinder of an internal combustion engine having upper and lower valve seats in the head thereof, of a valve arranged to engage said lower 85 seat, an auxiliary valve arranged to engage said upper seat, each of said valves having a face arranged to engage the face of the other valve for controlling the passage of 90 gases, and means for causing the separation of the engaged valves at predetermined times to permit the passage of gases therebetween.

OTTO J. F. FAJEN.
